[57] CLAIM

The ornamental design for a telephone, as shown and described.

DESCRIPTION

FIG. 1 is an isometric view of a telephone showing my new design;

FIG. 2 is a front elevational view of the telephone with the handset omitted for convenience of illustration;

FIG. 3 is a top plan view thereof;

FIG. 4 is a side elevational view thereof, the opposite side being a mirror image;

FIG. 5 is a perspective view of the handset, the telephone being omitted for convenience of illustration;

FIG. 6 is a front elevational view of the handset; and,

FIG. 7 is a side elevational view of the handset, the opposite side being a mirror image.

A characteristic feature of this design is that the back-board is transparent and is trimmed with a tubular neon light or similar light, and the earpiece is textured to resemble the texture of a basketball and is made of plastic or rubber.
